UNITED STATES PATENT OFFICE.

HERBERT GEORGE HENNE, OF NEW BRAUNFELS, TEXAS, ASSIGNOR TO NATIONAL ANTI-TIPPING LEAGUE, INCORPORATED, OF DALLAS, TEXAS.

DESIGN FOR A BADGE, BUTTON, OR SIMILAR ARTICLE.

41,551.

Specification for Design.

Patented July 11, 1911.

Application filed October 20, 1910. Serial No. 589,224. Term of patent 14 years.

To all whom it may concern:

Be it known that I, HERBERT GEORGE HENNE, a citizen of the United States, residing at New Braunfels, in the county of Comal and State of Texas, have invented a new, original, and ornamental Design for a Badge, Button, or Similar Article, of which the following is a specification, reference being had to the accompanying drawing, forming a part thereof.

The figure is a plan view showing my new design.

The article of manufacture on which my design is particularly used is a button.

I claim:

The ornamental design for a badge, button, or similar article, as shown.

HERBERT GEORGE HENNE.

Witnesses:

J. R. FUCHS,

R. A. LUDWIG.
